COATED ABRASIVE BACK-UP PAD FOR A ROTARY POWER SANDER OR THE LIKE

Dirck J. Olton, Loudonville, N.Y., assignor to Norton
Company, a corporation of Massachusetts

Filed Mar. 23, 1960, Ser. No. 59,839

Term of patent 14 years

(Cl. D37—1)

FIG. 1

FIG. 2

FIG. 3

FIG. 4

FIGURE 1 is a top plan view of a coated abrasive back-up pad for a rotary power sander or the like embodying my new design, the bottom being plain and unornamented;

FIGURE 2 is a side elevational view thereof, a portion of the pad being broken away to show its surface configuration and the retainer nut being omitted for convenience of illustration;

FIGURE 3 is an enlarged fragmentary view thereof showing a portion of the knurled surface; and

FIGURE 4 is a top plan view of a modified form thereof.

The characteristic features of my design for the disclosed coated abrasive back-up pad for a rotary power sander or the like, reside in the concentric knurled pattern as shown.

I claim:

The ornamental design for a coated abrasive back-up pad for a rotary power sander or the like, as shown and described.
